UNITED STATES PATENT OFFICE.

JAMES WILLIAM FEELER, OF BUHL, IDAHO.

CLOVER-HULLER.

1,190,137.

Specification of Letters Patent.

Patented July 4, 1916.

Application filed April 5, 1916. Serial No. 89,039.

To all whom it may concern:

Be it known that I, JAMES W. FEELER, a citizen of the United States, and a resident of Buhl, in the county of Twin Falls and State of Idaho, have invented a new and Improved Clover-Huller, of which the following is a full, clear, and exact description.

My invention relates to clover hullers involving a cylinder and a concave, and has for an object to provide a construction that may be cheaply produced for the most part from elements and materials readily available.

The invention also has for an object to provide a clover huller improved in various particulars with a view to promote strength and efficiency, effectiveness in operation, and convenience in the adjustment of the parts.

The invention will be particularly explained in the specific description following.

Reference is to be had to the accompanying drawings forming part of this specification in which similar reference characters indicate corresponding parts in all the views.

Figure 1 is an end elevation of a clover huller embodying my invention; Fig. 2 is a sectional plan view; Fig. 3 is a longitudinal vertical section; and Fig. 4 is a transverse vertical section.

My improved clover huller includes a suitable frame 10, mounted in which is a cylinder, designated generally by the numeral 11, the construction of which cylinder will be more particularly explained hereinafter.

The cylinder is secured to a shaft 12 turning in bearings 13 on the frame 10 and driven in any suitable manner as by a belt (not shown), running over a pulley 12^a. A housing or casing 14 is provided with hinged covers 15 at the top to afford access to the interior, and at the bottom, the casing is provided with a discharge spout 16.

A concave, designated generally by the numeral 17, is provided. At the upper end the concave 17 is supported on a bar 18 resting on the end members of the frame 10. The concave is formed of sheet metal which is bent downwardly at its lower end as at 19 to rest on a transverse rod 20. The bar 18 is preferably faced with a wear plate 21.

As seen best in Fig. 2, the concave, at its upper end, is curved transversely, or depressed on rounding lines, as at 22, the cross bar 18 and its wear plate 21 being similarly curved as at 23 to conform to the concave. The transverse curving of the concave pro-

duces a throat between the same and the cylinder 11 into which the clover is delivered by a spout 24.

In order to produce a strong and cheap cylinder, I form the same from a pulley 25 having a hub 25^a secured on the shaft 12 and I face said pulley with rasp sections 25^b, which may be formed in rings or sectors. Similarly, the sheet metal concave 17 is faced with rasp sections 17^a. The result is a very effective cylinder and concave, and also, the facing of the cylinder may be renewed without discarding the pulley and the cylinder thus maintained in proper condition at little cost.

In order to adjust the concave at its upper end and to release the same for the removal of stone or other foreign matter, I provide on the bar 18, threaded studs 26 which extend through brackets 27 suitably bolted to the frame 10. The said studs are provided with set nuts 28 at opposite sides of said brackets.

To provide for adjusting the lower end of the concave 17, the supporting rod 20 thereof, is carried in blocks 29 slideable vertically in boxings 30 and provided with studs 31 having set nuts 32 to adjust the height of the said blocks.

Having thus described my invention I claim as new, and desire to secure by Letters Patent:

1. A clover huller including a housing having a discharge outlet at the bottom, a cylinder mounted to turn in the housing, a concave, said concave being formed of sheet metal and having its lower end turned downwardly at the said discharge outlet, a transverse rod supporting the said lower end of the concave, an adjustable transverse bar on which the concave rests at its upper end, means for adjusting said transverse rod to and from the cylinder, means for adjusting said transverse bar to and from the cylinder, the transverse bar having a depression presenting a transversely concaved surface and the concave being correspondingly curved presenting an inlet throat, and means to deliver material to said throat.

2. A clover huller including a cylinder, a concave formed of sheet metal and having its lower end bent downwardly, a transverse rod supporting the said downturned end, a transverse bar, means for adjusting said bar to and from the cylinder, the said bar having a depression transversely curved, and

- the concave being correspondingly curved and presenting an inlet throat between said curved portion and the cylinder, and means to deliver material to said throat.
3. A clover huller including a cylinder, a concave formed of sheet metal and having its lower end bent downwardly, a transverse rod supporting the said downturned end, a transverse bar, means for adjusting said bar to and from the cylinder, the said bar having a depression transversely curved, a plate secured to the said bar and having a depression curved to correspond with the depression in the bar, the concave being correspondingly curved and presenting an inlet throat between said curved portion and the cylinder, and means to deliver material to said throat.

4. A clover huller including a cylinder, a concave, means to support the lower end of the concave, a transverse bar supporting the upper end of the concave, and formed with a depression concaved transversely, the said concave having a depression curved to correspond with the depression of the said supporting bar, and rasp sections on the face of the concave, said rasp sections at the depressed portion of the concave being formed to correspond with said depression.

In testimony whereof I have signed my name to this specification in the presence of two subscribing witnesses.

JAMES WILLIAM FEELER.
